UNITED STATES PATENT OFFICE.

MAURICE RATEL, OF NEW YORK, N. Y.

UNDERFEED STOKER.

Application filed August 29, 1921. Serial No. 496,509.

(GRANTED UNDER THE PROVISIONS OF THE ACT OF MARCH 3, 1921, 41 STAT. L., 1313.)

To all whom it may concern:

Be it known that I, MAURICE RATEL, a citizen of the Republic of France, and a resident of New York city, N. Y., have invented 5 new and useful Improvements in Underfeed Stokers (for which I have filed applications in France, March 30, 1914, No. 470, 231; England, June 18, 1920; Patent No. 145,458; Germany, June 26, 1920; Belgium, 10 June 14, 1920, Patent No. 360,616; Italy, June 15, 1920; Spain, June 16, 1920), which invention is fully set forth in the following specification.

This invention relates to automatic 15 stokers and more particularly to automatic stokers of the underfeed type, and it has for its object to provide a device of this character which overcomes serious defects and disadvantages inherent in automatic under- 20 feed stokers heretofore employed.

The stokers of this type heretofore suggested have been more or less defective in operation and expensive in maintenance, both for fuel and repairs. In the first place 25 they tend to produce an uneven distribution of fuel transversely of the twyters, and consequently an imperfect combustion due to the unequal supply of air to different parts of the fuel bed: A section made transversely 30 through the layer of fuel in these prior devices shows that the thickness of the fuel bed is not uniform but sinuous, and that the maximum thickness thereof occurs at the center of the fuel retorts or troughs. The 35 air being fed through the twyters along the two sides of the mass of fuel pushed into the retort, the fuel adjacent the walls of the retort is the first to be ignited and is consumed more rapidly than the greater mass of 40 fuel at the center of the retort. In the use of pulverized or other low-grade fuels, or fuels producing a fusible ash, fusion of the fuel takes place near the twyters with the formation of vitrified masses or clinkers 45 which surround and adhere to the large mass of fuel at the center of the retort, preventing the passage of air through the latter and loss of a large portion of the fuel. Furthermore, the rapid burning of the lateral portions 50 of the fuel in the retorts produces openings in the fuel bed through which excess air is blown with the resultant loss of

heat and the formation of flame jets which are injurious to the boiler and which are deflected by the vitrified masses or clinkers 55 back against the twyters and cause rapid deterioration of the latter with a consequent expensive maintenance for repairs.

In the second place, the clinker grinders heretofore employed in automatic stokers of 60 this type are generally arranged to operate on incandescent slag or clinker, which results in rapid deterioration of the grinding mechanism and increased cost of maintenance. Furthermore, the fuel liberated by 65 the clinker grinder, and which could otherwise be utilized, is remote from the air supply, so that the same is ejected into the ash pit and lost, thus increasing the expense of 70 operation of the stoker.

In the third place, the rocking mechanism used in automatic stokers heretofore employed for discharging the ashes and clinkers requires an attendant, which increases the cost of maintenance, and the mechanism 75 is seriously defective for the reason that, during its operation, air enters between the interstices of the dumping plates and continues to enter until the same are covered by 80 ashes, thus causing an uneven burning of the fuel and assisting in the formation of slag or clinker.

It is an object of the present invention to overcome these defects and disadvantages by providing, in combination with an automatic 85 underfeed stoker having an inclined fuel bed support, means whereby all grades of fuel may be used and insuring complete combustion of the fuel in all parts of the fuel bed.

Another object of this invention is to provide an even distribution of air and fuel to all parts of the fuel bed by causing a continuous undulatory or shearing movement 90 of the entire mass of fuel.

A further object of this invention is to provide fuel-feeding mechanism in the fuel retorts constructed and arranged so as to impart a plowing movement to the fuel bed whereby the formation of clinkers or vitrified masses is prevented.

A further object of this invention is to prevent the formation of vitrified masses of fuel in the fuel retorts by providing fuel-

feeding mechanism arranged in each retort so as to operate in the fresh fuel close to the twyer air inlets.

A further object of this invention is to 5 provide a more even distribution of fuel to the fuel bed by the use of a plurality of fuel-feeding members in each retort and adjacent to the respective tuyers.

A further object of this invention is to 10 provide improved mechanism for interrupting the strokes of the fuel-feeding members to facilitate agitation of the fuel bed.

A further object of this invention is to 15 provide, in combination with fuel-feeding mechanism of the type referred to, fuel-crushing and ash-ejecting mechanism at the bottom of the inclined fuel bed support and provided with a combustion-supporting or oxidizing fluid supply whereby complete 20 combustion of the fuel at the bottom of the inclined fuel bed support is effected.

A further object of this invention is to 25 provide, in combination with an automatic underfeed stoker of the type referred to, reciprocating crushing and ash-collecting and discharging means at the bottom of the fuel bed support, together preferably with a combustion or oxidizing fluid supply for the material operated upon by said crushing 30 mechanism.

Other objects relate to the provision of an 35 automatic underfeed stoker which is simple in construction, efficient in operation, inexpensive to maintain, and economical in its use of fuel.

Broadly stated, the invention comprises 40 an automatic underfeed stoker having a series of alternating tuyers and retorts or troughs both arranged to provide an inclined fuel bed support, whereby the fuel and solid products of combustion are fed downwardly with the aid of gravity, a plurality of fuel-feeding members disposed within each retort and operatively connected 45 with the main power shaft of the stoker, said fuel-feeding members operating in the fresh fuel below the twyer air-inlets and formed and arranged to exert a plowing action on the fuel and effect even distribution thereof to maintain a fuel bed of substantially uniform thickness. A receiving grate or grates are preferably provided at the bottom of the inclined fuel bed support for receiving the fuel and solid products of combustion 50 from the inclined fuel bed support proper, said receiving grate or grates desirably having means for regulating the air supply therethrough. Reciprocating crushing mechanism is also preferably provided 55 for pulverizing the unburned fuel, clinkers, and ashes passing over said receiving grates from said inclined fuel bed support, said crushing mechanism being operatively connected with the fuel-feeding mechanism and 60 having adjacent thereto a combustion-sup-

porting or oxidizing fluid supply for the material delivered thereto. Ash-collecting and discharging means are also shown at the lower side of the inclined fuel bed support whereby the ashes and refuse may be effectively handled for dumping into the ash pit.

The invention is capable of receiving a variety of mechanical expressions, some of which are shown in the accompanying drawings, but it is to be expressly understood that the drawings are for the purpose of illustration only and are not to be construed as defining the limits of the invention, reference being had to the appended claims for that purpose.

In said drawings:

Fig. 1 is a longitudinal section through an automatic underfeed stoker embodying the present invention;

Fig. 2 is a plan view of the stoker shown in Fig. 1 with the fuel hoppers removed;

Fig. 3 is a front elevation of one of the secondary fuel feeding members shown in Fig. 2;

Fig. 4 is a side elevation of the secondary fuel feeding member shown in Fig. 3;

Fig. 5 is a side elevation of another secondary fuel feeding member which may be employed in the secondary pushers shown in Figs. 1 and 2;

Fig. 6 is a fragmental side elevation of the main fuel-feeding member and a stop mechanism for interrupting the rearward movement of the secondary fuel feeding members;

Fig. 7 is a fragmental front elevation of part of the mechanism shown in Fig. 6;

Fig. 8 is a detail of a stop member forming part of the stop mechanism shown in Figs. 6 and 7;

Fig. 9 is a longitudinal section through another automatic stoker embodying the present invention showing another secondary fuel-feeding mechanism;

Fig. 10 is a transverse section on the line 10-10 of Fig. 9;

Fig. 11 is a vertical section showing still another secondary fuel feeding mechanism embodying the present invention, which may be employed as the secondary fuel feeding mechanism shown in the embodiment of Figs. 9 and 10; and

Fig. 12 is a fragmental side elevation of the secondary fuel-feeding mechanism shown in Fig. 11.

The present invention is applicable to a wide variety of boilers and forms of furnaces and, therefore, as it is not limited to any particular type of boiler construction the details of the latter have not been illustrated.

In the embodiment shown in Figs. 1 and 2, the automatic stoker consists of a series of alternating and inclined fuel retorts or troughs 1 and tuyers 2 of any suitable construction. Said tuyers and retorts or

troughs accordingly provide downwardly inclined fuel-supporting surfaces whereby the advancing movement of the fuel bed is effected with the aid of gravity. The fuel 5 is fed to the retorts from the hoppers 3 by a plurality of main fuel-feeding members 4, one at the upper end of each retort, and feeding of the fuel from the retorts and even distribution of the fuel to the entire fuel bed 10 is effected by a plurality of compound pushers each of which comprises a plurality of secondary fuel-feeding members 5. As shown, each retort contains a set of compound pushers laterally disposed with respect to each other and preferably arranged side by side within the retort, and the secondary fuel-feeding members of said compound pushers are disposed on both sides and at a distance from the longitudinal center 15 of the retort close to the side walls thereof and adjacent to the twyer air inlets. Said compound pushers have their longitudinal axis disposed in different vertical planes and the secondary fuel-feeding members preferably have the form of plow-shares and exert a plowing action on the fuel. As shown in Fig. 1, the secondary fuel-feeding members may be of progressively decreasing feeding capacity and are of progressively decreasing size and arranged in stepped relation within the retort, and, as shown more particularly in Figs. 3 and 4 inclusive, said secondary fuel-feeding members may be individually formed with steps or serrations 20 which operate in the fuel adjacent the lowermost twyer air inlets. As shown in Fig. 5, the serrations of secondary fuel feeding member 5' are differently formed as respects the serrations of secondary fuel feeding member 5. The compound pushers comprised by secondary fuel-feeding members 5 are fixed or secured in any suitable manner to rods 6, and said main fuel-feeding members or rams 4 are operatively connected to 25 the cranks 7 of a power shaft 8 by connecting rods 9. Said power shaft may be driven by any suitable source of power, and any other suitable means may be used for connecting the main fuel-feeding members or rams with the source of power, such as a steam piston or eccentrics arranged in suitable spaced relation on the power shaft and strap connections. The rods 6 are slidably mounted in suitable openings 10 and 11 at 30 the ends of each retort or trough, and at the front ends said rods are provided with a plurality of holes 12 in which may be arranged pegs or pins 13 and 13' forming stops which are engaged respectively by a depending lug 14 of the main fuel-feeding member or ram 4, whereby said secondary fuel-feeding members are reciprocated to feed the fuel from the retort to the inclined fuel bed. By moving the pins 13 and 13', the strokes of the compound pushers comprised by secondary 35 fuel-feeding members 5 may be varied with respect to the strokes of the main fuel-feeding members or rams 4. The angle of inclination of the twyers 2 is shown as greater than that of the retorts or troughs 1, and as the secondary fuel-feeding members are reciprocated, they will move the fuel in both substantially horizontal and vertical directions owing to the inclination of the line of travel of said members, thus imparting agitation and an undulatory movement to the entire mass of fuel on the fuel bed. Any other suitable mechanism may be provided for driving the compound pushers, for example cams or eccentrics cooperating with said pushers and arranged in suitably spaced relation on a driving shaft, or a crank shaft and connecting rods cooperating with said compound pushers. Instead of a plurality of main fuel-feeding members or rams, a single ram may be provided and driven by any suitable mechanism.

In the embodiment of the present invention above referred to, undulatory and cutting or shearing movements of the entire mass of fuel are effected by so articulating the main fuel-feeding members with the power shaft 8 that alternate main fuel-feeding members will be moved in opposite directions and no two adjacent main fuel-feeding members can simultaneously move in the same direction throughout their respective strokes (Fig. 2). The secondary fuel-feeding members in successive retorts will, therefore, have successive advancing movements, and in alternate retorts the secondary fuel-feeding members will be reciprocated in opposite directions. Furthermore, the secondary fuel-feeding members in any two adjacent retorts cannot move simultaneously in the same direction throughout their respective strokes.

Means are preferably provided for automatically connecting and disconnecting the compound pushers during the forward movement thereof to effect cutting or a shearing movement of the entire mass of fuel, and, in the form shown, said means comprises a stop member 15 pivotally mounted in the path of travel of the depending lug 14 and journaled in suitable bearings in the lower ends of and between a pair of depending brackets 16 and 17 secured in any suitable manner to the rods 6, near the outer ends thereof respectively. Secured to one side of the stop member 15 in any suitable manner is a rod 18 provided at the outer end thereof with a roller 19 travelling on an upper guide 20 and a lower guide 21. The lug 14 engages the stop member 15 during forward movement of the main fuel-feeding member, thereby moving the secondary fuel-feeding members forward for a certain distance. At any suitable point, the upper guide 20 is terminated so that, during 130

forward movement of the secondary fuel-feeding members, the roller 19 escapes and the stop member is depressed rearwardly about the axis 22 by the lug 14, thereby disconnecting and interrupting movement of the secondary fuel-feeding members, after which the latter are returned to the end of their forward stroke by engagement of the lug 14 with the pegs or pins 13. After the lug 14 passes over the stop member, the rod 18 and roller 19 will act as a counterweight to bring the stop member back to its normal vertical position, the roller 19 then resting on the lower guide 21. While the lug 14 is in engagement with the stop member to move the secondary fuel-feeding members forward, the stop member is prevented from turning, in a direction opposite to that indicated by the arrow in Fig. 8, by a shoulder 23 formed at the bottom thereof and engaging an abutment 24 of the rod 18. In order to insure even distribution of the fuel while at the same time providing for cutting or a shearing movement of the same, the pins or pegs 13 and 13' are preferably placed on the rods 6 at the same distance from the forward ends thereof, so that the compound pushers or secondary fuel-feeding members will be in alinement during the rearward movement thereof.

On rearward movement of the main fuel-feeding member or ram 4, the stop member 15 is depressed by the lug 14, the stop member turning about its axis in the direction indicated by the arrow in Fig. 8. After the lug 14 passes over the stop member, said lug engages the pins 13', thereby moving the secondary fuel-feeding members rearwardly, the stop member being returned to its normal vertical position by a coil spring 25, the respective ends of which are secured in any suitable manner to the outer ends of the shoulder 23 and abutment 24.

In the present embodiment of the invention, the stoker is provided at the lower side of the inclined fuel bed with a stationary receiving grate or grates 26 forming a continuation of the inclined fuel bed and over which pass the products of combustion and unburned fuel from the inclined fuel bed. Said receiving grate or grates may be of any suitable form and, if desired, movable in any desired manner by any suitable mechanism. The receiving grate or grates and the inclined fuel bed support both may be provided with any suitable combustion-supporting or oxidizing fluid supply, shown in the form of a main conduit 27 which communicates with a conduit 28 leading to the under side of the inclined fuel bed support and grates and through which the combustion-supporting or oxidizing fluid is blown and the supply thereof regulated by any suitable means in the usual manner. Said receiving grate or grates may be provided with means for regu-

lating the supply of combustion-supporting fluid as shown in the form of a damper 29 journaled in any suitable manner in the framework of the stoker, below the fuel bed support and said grate, and operated in any suitable manner.

The crushing mechanism embodying the present invention comprises a plurality of hollow crushing members or rams 30 slidably mounted between transversely extending conduits 31 and 32 provided, respectively, with apertures 33 and 34, said conduits having a combustion-supporting or oxidized fluid supply in the form of air, steam, humid air, saturated steam, or combinations thereof, which is forced in the form of jets through said apertures in any suitable manner for contact with the material delivered to the fuel-crushing mechanism. The combustion-supporting fluid coming in contact with the burning clinkers will dissociate with the subsequent formation of combustible gases, and, moreover, cause disaggregation of the mass of clinkers, whereby easy crushing of the same will be facilitated. The supply of combustion-supporting fluid to the pulverized material will insure complete combustion of unburned particles of fuel liberated by the crushing of the clinkers. Each crushing member or ram 30 is reciprocated by means of links 35, 35^a, 35^b, and 35^c and levers 35^d and 35^e pivotally connecting them with the ram 4. Said crusher mechanism is further preferably combined with suitable ash-discharging means in the form of a plurality of reciprocating grates 36 for discharging the ashes and solid products of combustion. As shown in the figure, each grate 36 is supported on rollers 37 mounted on a suitable framework 38 positioned vertically below the fuel-crushing mechanism. Said grate is provided at the rear thereof with an enlarged portion forming a ram or ejector 39, the forward face of which may be indented to form steps as clearly shown in the drawings. Said grate is given a reciprocating motion in a direction opposite to that of the fuel-crushing member or ram 30, the former being pivotally connected with the links 35^b which is moved by the main fuel-feeding member 4. This opposite direction of movement of the grates 36 and the crushing members or rams 30 provides for a continuous supporting, crushing and ejecting of the material and allows the same to completely absorb the combustion-supporting or oxidizing fluid so as to completely consume the unburned particles of fuel before ejection of the pulverized material by the grate and ram 39. The rearward movement of the grate is accommodated by a chamber forming part of the rear wall of the furnace, and said wall is also provided with a chamber or conduit forming a part of the wall above the ash-eject-

ing grate and through which combustion-supporting or oxidizing fluid may be circulated in any suitable manner and ejected through suitable apertures 40 to the material delivered to the crushing mechanism. Means are provided for varying or adjusting the strokes of the crushing members and reciprocating grates and, as shown, the pair of rods 35 connected with the main fuel-feeding members are provided with a plurality of apertures 35' whereby the peg or pin 35", which extends through a suitable aperture in the lug 14 and aligned apertures in said rods 35, may be moved to engage in any of the apertures 35', as desired.

Figs. 9, 10, 11 and 12 illustrate another automatic underfeed stoker embodying the present invention, comprising a main grate composed of a series of twyers 41 of any suitable construction successively diminishing in elevation from a medial fore and aft line toward the sides of the furnace, so as to provide a grate of the gravity-feed type, said twyers being separated by fuel retorts 42 at and on both sides of said medial line. Said troughs or retorts are shown as of successively decreasing cross-section, but they may be of successively decreasing width, successively decreasing depth, or both. The fuel is supplied to the grate from the hopper 43 by fuel-feeding devices effecting an even distribution of the fuel to maintain a fuel bed of substantially uniform thickness. Said devices preferably comprise a main fuel-feeding member 44 at the outer end of each retort and one or more compound pushers in the retort, Figs. 11 and 12 showing a set or plurality of compound pushers in the retort laterally disposed with respect to each other. The compound pushers have their longitudinal axes disposed in different vertical planes and each compound pusher comprises a plurality of oscillating or vertically moving secondary fuel-feeding members disposed within each retort. Said main fuel-feeding member may be actuated in any suitable way as by crank mechanism from the main power shaft 46, and the secondary fuel-feeding members 45, which as shown are wedge-shaped in the vertical sense, are pivotally connected at their forward ends in any suitable manner with a reciprocating member or plate 47, providing a bottom for the retort and slidably mounted in grooves at the lower ends of the side walls 48 of said retort. The reciprocating plate 47 extends beyond the forward wall of the furnace and is bifurcated to provide a pair of rods 49 each having a plurality of apertures 50 and between which depends a lug 51 integrally formed on of the main fuel-feeding member and adapted to engage pegs or pins 52 and 52' inserted in the apertures 50 for imparting reciprocating motion to the plate

47. The secondary fuel-feeding members or pushers of the device shown in Fig. 1, the stop mechanism shown in Figs. 6-8, or both, may be used in the device shown in Fig. 9.

In addition to the horizontal feeding motion imparted to the secondary fuel-feeding members, vertical and oscillating motion is also imparted to the latter, the successive fuel feeding members preferably being moved in opposite directions during their translatory movement, by means of rods 53 pivotally connected in any suitable manner at their upper ends with the secondary fuel feeding members and bifurcated to receive rollers 54 suitably journaled in the bifurcations of said rods and each engaging a cam 55 disposed adjacent to the retort and preferably below the same. While a separate cam may be provided for each secondary fuel feeding member 45', the cams are preferably constituted by a sinuous groove or slot formed in a guide bar 56 positioned vertically below the slidable plate 47 and secured to the furnace structure in any suitable manner.

In the form shown in Figs. 11 and 12, agitation of the fuel bed is obtained by a set of compound pushers arranged side by side, in the retort 42'. The compound pushers, here shown as two in number, are comprised by a plurality of secondary fuel feeding members 45', 45" pivotally connected at their forward ends with reciprocating plate 47', the laterally adjacent secondary fuel feeding members and the successive secondary fuel feeding members which extend longitudinally of the retort 48', both preferably having vertical or oscillating movement in opposite directions. The construction of the secondary fuel-feeding members and operating mechanism therefor is identical with that shown in Figs. 9 and 10, except that two compound pushers and operating mechanism therefor are provided, the cams 55', 55" preferably being constituted by sinuous grooves or slots in the two guide bars 56', 56" and having relatively opposite curvatures whereby laterally adjacent fuel feeding members of the compound pushers and successive fuel feeding members of the same extending longitudinally of the retort, are both moved in opposite directions during their translatory movement, through the medium of connections to be presently described. These connections preferably comprise rods 53', 53" pivotally connected in any suitable manner at their upper ends with members 45', 45" and bifurcated at their lower ends to receive rollers 54', 54" suitably journaled in the bifurcations of said rods and engaging in the sinuous grooves forming cams 55', 55". The stroke of the secondary fuel-feeding members, in each case, may be varied

with respect to the main fuel-feeding members by changing the position of the pegs or pins 52 and 52', and the number of secondary fuel-feeding members may be increased 5 or decreased according to the size of the retorts.

At the bottom of the inclined fuel bed support in the form shown, at either side thereof, is a receiving grate or grate 57 over, 10 which pass the ashes and unburned fuel from the inclined fuel bed proper. Combustion-supporting or oxidizing fluid is supplied to said fuel bed support and said grates in any suitable manner as by forcing said, 15 fluid in the usual manner through a main conduit 58 communicating with a chamber 59 below said fuel bed. The supply of combustion-supporting or oxidizing fluid to the receiving grate or grates 57 may be regulated by suitable dampers 60 mounted in the framework of the stoker and operated in any suitable manner. The side walls of the furnace are reduced to form a housing for the crusher mechanism at both sides of the fuel bed, said crusher mechanism comprising, 20 hollow plungers or rams 61 supported on suitable rollers 62 mounted on the walls of the furnace. Said fuel-crushing members or rams are reciprocated by mutilated gears 25 63 having engagement with racks 64 on the sides of the fuel-crushing members or rams, the gears 63 being keyed to shafts 65 operated by any suitable mechanism which may be operatively connected with the main, 30 power shaft of the stoker. As clearly shown, the inclined fuel bed support and grates are arranged in spaced relation with the furnace wall to provide discharge openings for the refuse or ashes, and below said openings, 35 are positioned receiving plates 66 pivotally mounted on the furnace walls in any suitable manner and having curved toothed brackets 67 pivotally connected therewith, the teeth of said brackets being adapted to, 40 engage stops or detents 68 whereby the size of the refuse or ash discharge openings may be regulated as desired. Said receiving plates are arranged to cooperate with the fuel-crushing members or rams 61 whereby, 45 after the slag, ashes, and clinkers are crushed, the same are pushed over the receiving plates 66 by the crushing members or rams and ejected into the ash pit.

It is to be expressly understood that features illustrated and described in one embodiment of this invention may be used in other embodiments of the invention, and certain features thereof are capable of use without other features thereof. Reference, 55 is therefore to be had to the claims hereto appended for a definition of the limits of the invention.

What is claimed is:—

1. In an automatic stoker, a series of al-

ternating stationary twyers and fuel retorts 65 or troughs, a main fuel feeding member for each retort, and a set of compound pushers disposed side by side in each retort and operatively connected with the main fuel feeding member, said compound pushers each 70 comprising a plurality of secondary fuel feeding members.

2. In an automatic stoker, a series of alternating stationary twyers and fuel retorts 75 or troughs, a main fuel feeding member for each retort, and a set of compound pushers disposed side by side in each retort and operatively connected with the main fuel feeding member, said compound pushers each 80 comprising a plurality of vertically movable secondary fuel feeding members.

3. In an automatic stoker, a series of alternating stationary twyers and fuel retorts 85 or troughs, a main fuel feeding member for each retort, and a set of compound pushers disposed side by side in each retort and each comprising secondary fuel feeding members of progressively decreasing capacity so as to feed progressively decreasing quantities 90 of fuel to the fuel bed.

4. In an automatic stoker, a plurality of fuel retorts or troughs, twyers alternating therewith, a main fuel feeding member for each retort, a set of compound pushers disposed side by side in each retort, and means 95 for adjusting the strokes of said compound pushers with respect to the main fuel feeding members.

5. In an automatic stoker, a series of alternating stationary twyers and fuel retorts 100 or troughs providing a fuel bed support, a set of compound pushers disposed side by side in each retort and each comprising a plurality of vertically movable secondary fuel feeding members, and a grate disposed 105 adjacent to said fuel bed support.

6. In an automatic stoker, a series of alternating stationary twyers and fuel retorts or troughs providing a fuel bed support, a set of compound pushers disposed side by side in each retort and each comprising a plurality of vertically movable secondary fuel feeding members, and crushing mechanism disposed adjacent to said fuel bed support.

7. In an automatic stoker, a main fuel feeding member, a secondary fuel feeding member, and driving connections between said fuel feeding members including means automatically making and breaking connection therebetween intermediate the limits of motion of the secondary fuel feeding member.

8. In an automatic stoker, a main fuel feeding member, a secondary fuel feeding member, and driving connections between said fuel feeding members including trip mechanism for automatically breaking con-

nexion between the fuel feeding members intermediate the limits of movement of the secondary fuel feeding member.

9. In an automatic underfeed stoker, a series of twyers successively differing in elevation from a medial fore and aft line of the furnace, fuel retorts or troughs on both sides of said medial line and alternating with said twyers, and means for feeding fuel through said retorts or troughs to said twyers comprising a main fuel-feeding member for each retort, a secondary fuel-feeding member disposed in each retort, and means for imparting translatory and oscillating motion to said secondary fuel-feeding member.

10. In an automatic stoker, a series of twyers successively differing in elevation from a medial fore and aft line of the furnace, fuel retorts or troughs on both sides of said medial line, and means for feeding fuel through said retorts or troughs to said twyers comprising a main fuel-feeding member for each retort, a plurality of secondary fuel-feeding members disposed in each retort, and mechanism for imparting translatory and oscillating motion to said secondary fuel-feeding members.

11. In an automatic stoker, a series of twyers successively differing in elevation from a medial fore and aft line of the furnace, fuel retorts or troughs on both sides of said medial line, reciprocating means for feeding fuel through said retorts to said twyers comprising a main fuel-feeding member at the forward end of each retort, a supporting member operatively connected with the main fuel-feeding member and disposed within the retort, a secondary fuel-feeding member pivotally connected with said supporting member, and means for moving said secondary fuel member about its pivot during movement of the supporting member.

12. In an automatic stoker, a series of twyers successively differing in elevation from a medial fore and aft line of the furnace, fuel retorts or troughs on both sides of said medial line, and means for feeding fuel through said retorts to said twyers comprising a main fuel-feeding member at the forward end of each retort, secondary fuel-feeding members within each retort and operatively connected with said main fuel-feeding member, and means for imparting vertical oscillating movement to said secondary fuel-feeding members.

13. In an automatic stoker, a series of twyers successively varying in elevation from a medial fore and aft line of the furnace, fuel retorts or troughs on both sides of said medial line, means for feeding fuel through said retorts to said twyers comprising a main fuel-feeding member at the forward

ward end of each retort, a reciprocating member within each retort forming the bottom thereof and operatively connected with the main fuel-feeding member, secondary fuel-feeding members pivotally connected with said reciprocating member, and means for oscillating successive secondary fuel-feeding members in opposite directions.

14. In an automatic stoker, a series of twyers decreasing in elevation from a medial fore and aft line of the furnace, fuel retorts or troughs on both sides of said medial line, said twyers and retorts providing a fuel bed support inclined from both sides of the furnace, grates at the bottom of said inclined fuel bed support, means for feeding fuel through said retorts to the fuel bed, movable refuse receiving means at the bottom of said fuel bed support and grates, and reciprocating means for crushing and ejecting refuse over said movable receiving means.

15. In an automatic stoker, a series of alternating twyers and fuel retorts or troughs, arranged to provide a fuel bed support, means for feeding fuel through said retorts to the fuel bed comprising a main fuel-feeding member at the forward end of each retort, a reciprocating member within each retort, secondary fuel-feeding members pivotally connected with said reciprocating member, and means for alternately oscillating successive secondary fuel-feeding members.

16. In an automatic stoker, a series of alternating twyers and retorts or troughs, a main fuel-feeding member for each retort, a secondary fuel-feeding member disposed in each retort, and means for imparting translatory and oscillating motion to said secondary fuel-feeding member.

17. In an automatic stoker, a series of alternating twyers and fuel retorts or troughs arranged to provide a fuel bed support, means for feeding fuel through each of said retorts to the fuel bed comprising a fuel-feeding ram for each retort and a plurality of fuel-feeding members pivotally mounted side by side in each retort, and means supplying a combustion supporting fluid to the fuel bed support.

18. In an automatic stoker, a series of twyers and retorts or troughs arranged to provide a fuel bed support, and means for feeding fuel through said retorts to the fuel bed comprising a main fuel-feeding member for each retort and a set of compound pushers in each retort, each compound pusher comprising a pair of secondary fuel-feeding members pivotally mounted side by side in the retort, and means for oscillating said members about their pivots.

19. In an automatic stoker, a series of alternating twyers and fuel retorts or troughs arranged to provide a fuel bed support, and

- means for feeding fuel through said retorts to said fuel bed comprising a main fuel-feeding member for each retort, a set of compound pushers disposed in each retort, each compound pusher comprising a pair of pivotally mounted secondary fuel-feeding members, and means for oscillating the members of each pair in opposite direction. 65
20. In an automatic stoker, a series of alternating twyters and fuel retorts or troughs arranged to provide a fuel bed support, means for supplying a combustion-supporting fluid to the fuel bed, means for feeding fuel through said retorts to said fuel bed 70
- 15 support comprising a main fuel-feeding member for each retort, a set of compound pushers disposed side by side in each retort, said compound pushers each comprising a plurality of pivoted secondary fuel-feeding 75
- 20 members, and means for oscillating successive pivoted members of each pusher in opposite directions. 80
21. In an automatic stoker, a series of alternating twyters and retorts, a main fuel-feeding member for each retort, a set of compound pushers disposed side by side in each retort, each compound pusher comprising a plurality of pivoted fuel-feeding members, and means for oscillating the corresponding 85
- 30 members of said pushers in opposite directions. 90
22. In an automatic stoker, a series of alternating twyters and fuel retorts or troughs arranged to provide a fuel bed support, 95
- 35 means for feeding fuel through said retorts to the fuel bed comprising a main fuel-feeding member for each retort and a set of compound pushers disposed side by side in each retort, each compound pusher comprising a plurality of pivoted fuel-feeding members, 100
- 40 means for oscillating successive fuel-feeding members of each pusher in opposite directions, and means providing for relative adjustment of the strokes of the main fuel-feeding member and said compound pushers. 105
23. In an automatic stoker, a series of twyters and retorts or troughs arranged to provide a fuel bed support, and means for feeding fuel through said retorts to the fuel bed comprising a main fuel-feeding member for each retort and a set of compound pushers disposed side by side in each retort, said compound pushers each including a plurality of independent movable elements, 110
- 50 and means for moving the laterally adjacent elements of said compound pushers in opposite directions. 115
24. In an automatic stoker, a fuel retort or trough, a fuel-feeding member pivotally mounted in said retort, means for imparting translatory movement to said fuel-feeding member, and means for oscillating the fuel feeding member during its translatory movement. 120
- 60
25. In an automatic stoker, a fuel retort or trough, a plurality of fuel-feeding members pivotally mounted side by side in the retort, and means for oscillating the adjacent fuel-feeding members in opposite directions. 125
26. In an automatic stoker, a fuel retort or trough, a plurality of pivoted fuel-feeding members in the retort, means for imparting translatory movement to said fuel feeding members, and means for oscillating the successive fuel-feeding members in opposite directions during their translatory movement. 130
27. In an automatic stoker, a fuel retort or trough, a set of compound pushers disposed side by side in the retort, and means for moving the adjacent elements of said compound pushers vertically in opposite directions. 135
28. In an automatic stoker, a fuel retort or trough, a set of compound pushers disposed side by side in said retort or trough, means for imparting translatory movement to said compound pushers, and means for moving the successive elements of each pusher in opposite directions during translatory movement of the latter, said means being adapted to move laterally adjacent elements of said pushers in opposite directions. 140
29. In an automatic stoker, a fuel retort or trough, twyters at the sides of said retort or trough, a main fuel feeding member for the retort and a set of compound pushers in said retort operatively connected with said main fuel feeding member, and having their longitudinal axes disposed in different vertical planes, each compound pusher including a vertically movable secondary fuel feeding member. 145
30. In an automatic stoker, a fuel retort or trough, a set of compound pushers in said retort having their longitudinal axes in different vertical planes, means for imparting translatory movement to said compound pushers, and means for moving laterally adjacent elements of said compound pushers vertically in opposite directions during their translatory movement. 150
31. In an automatic stoker, a fuel retort or trough, a fuel-feeding ram for said retort, a set of compound pushers in the retort having their longitudinal axes in different vertical planes, and means for adjusting the strokes of said pushers with respect to the fuel feeding ram. 155
32. In an automatic stoker, a fuel retort or trough, twyters at the sides of said retort or trough, a fuel feeding ram for the retort, a secondary fuel feeding member in said retort, means connecting said ram with the secondary fuel feeding member for imparting translatory movement to the latter, 160

and means imparting vertical movement to said secondary fuel feeding member during its translatory movement.

33. In an automatic stoker, a fuel retort or trough, twyters at the sides of said retort, a fuel-feeding ram for said retort, a set of compound pushers in the retort and disposed laterally with respect to each other, means connecting said ram with the compound pushers for reciprocating the latter, and means for adjusting the strokes of said pushers with respect to the fuel feeding ram.

34. In an automatic stoker, a fuel retort or trough, a fuel feeding member in said retort, means for imparting translatory movement to the fuel feeding member, and means for moving said member vertically during its translatory movement.

35. In an automatic stoker, a fuel retort or trough, a compound pusher in said retort and comprising a plurality of vertically movable fuel-feeding elements, and means for imparting translatory movement to said compound pusher.

36. In an automatic stoker, a fuel retort or trough, a set of compound pushers disposed side by side in said retort and each comprising a plurality of vertically movable fuel feeding elements, means for imparting translatory movement to the compound pushers, and means for varying the strokes of said compound pushers.

37. In an automatic stoker, a fuel retort or trough, a compound pusher in said retort and comprising a plurality of vertically movable fuel feeding elements having progressively decreasing feeding capacity toward the rear of the furnace, and means for imparting translatory movement to said compound pushers.

38. In an automatic stoker, a fuel retort or trough, a set of compound pushers disposed side by side in said retort and each including a vertically movable secondary fuel feeding element, and a grate arranged adjacent to said retort.

39. In an automatic stoker, a fuel retort or trough, a set of compound pushers disposed side by side in said retort and each including a vertically movable secondary fuel feeding element, and a crusher arranged adjacent to said retort.

40. In an automatic stoker, a fuel retort or trough, a set of compound pushers disposed side by side in said retort and each including a vertically movable secondary fuel feeding element, a refuse collecting and receiving device arranged adjacent to said retort, and a refuse crushing device adapted to eject the refuse over said collecting and receiving device.

41. In an automatic stoker, a series of alternating twyters and fuel retorts or troughs,

a set of compound pushers disposed side by side in each retort and each including a vertically movable fuel feeding element, and means for imparting translatory movement to said compound pushers.

42. In an automatic stoker, a fuel feeding member, a driving member, and means imparting uninterrupted motion in one direction to the fuel feeding member from said driving member and imparting intermittent motion in the opposite direction to said fuel feeding member from the driving member, said means including devices automatically connecting said members and disconnecting the same for a predetermined interval intermediate the limits of movement of the fuel feeding member.

43. In an automatic stoker, a driving member, a fuel feeding member, and connections between the driving member and the fuel feeding member including trip mechanism for breaking connection between said driving member and the fuel feeding member intermediate the limits of movement of the latter.

44. In an automatic stoker, a fuel retort or trough, a driving member, a fuel-feeding member driven by said driving member, a device pivoted on said driven member and having an arm extending therefrom, a yieldable trip or detent pivoted on said device for connecting the driven and driving members on movement of the latter in one direction, said trip being depressed by the driving member in its opposite movement, and a guide terminating at a point between the limits of movement of the driven member, said arm having intermittent engagement with said guide during reciprocation of the fuel-feeding member.

45. In an automatic stoker, a pusher bar or plate, means for imparting translatory movement to said bar or plate, a cam, a fuel-feeding element pivoted on the pusher bar or plate, and a member secured to said fuel-feeding element and engaging said cam.

46. In an automatic stoker, a pusher bar or plate, means for imparting translatory movement to said bar or plate, two oppositely curved cams, two fuel-feeding elements pivoted on said pusher bar or plate, and members secured to said elements and engaging said cams.

47. In an automatic stoker, a pusher bar or plate, means for imparting translatory movement to said bar or plate, a plurality of cams, a plurality of fuel-feeding elements pivoted along said bar or plate, and members secured to said fuel-feeding elements and engaging said cams.

48. In an automatic stoker, a pusher bar or plate, means for imparting translatory movement to the bar or plate, a pair of fuel-feeding elements pivoted side by side on

said bar or plate, and means for oscillating said elements in opposite directions during their translatory movement.

49. In an automatic stoker, a pusher bar or plate, and means for oscillating the adjacent fuel-feeding elements in opposite directions during their translatory movements. 10
5 or plate, means for imparting translatory movement to the bar or plate, pairs of fuel-feeding elements pivoted along said bar or

In testimony whereof I have signed this specification.

MAURICE RATEL.
